SEPARABLE ELECTRICAL CONTACT DEVICE

Carl L. Knutson, Maywood, Ill., assignor to Cinch
Manufacturing Corporation, Chicago, Ill., a
corporation of Illinois

Application September 9, 1933, Serial No. 688,804

5 Claims. (Cl. 173—332)

My invention relates to improvements in a separable electrical contact device.

In the drawing which illustrates a preferred embodiment of my invention:

5 Figure 1 is a section through the entire device, embodying my invention but without the wiring cables;

10 Fig. 2 is a plan section on the line 2—2 of Fig. 1, showing the position of the members before being rotated to assemble the several parts;

15 Fig. 3 is a plan section similar to Fig. 2 but showing the parts rotated to assembled positions; and

20 Fig. 4 is a bottom plan view of the top member shown in Fig. 1.

25 My invention as illustrated by the drawing relates to an improvement in separable electrical contact devices though more particularly to provide means for correct alignment of male and female electrical contacts as well as a new improved method of assembling what is known as a cable plug for radio or like apparatus to a plate supporting a plurality of the aforesaid male or female contact members.

30 The particular device illustrated herein includes cable plugs having cup-shaped housings 1 and 1a and a plurality of plate portions 2 and 3 of insulating material carrying male and female electrical contact devices respectively and 35 being adapted for yieldable interengagement with each other and for engagement with the cable plug or housing members 1 and 1a.

35 The member 2 comprises superposed plates 4 and 5 of insulating material spaced in substantially parallel relation by a smaller plate 6. The plate 4 carries a number of smooth tubular male projections 7 secured thereto, as by riveting, and arranged about the plate 4 in a manner to be described hereinafter.

40 The member 3 comprises plates 8 and 9 which are arranged in spaced relation by a plate 10 and the shape and arrangement of each plate are about the same as those of the member 2. The plate 8 has a plurality of holes through which 45 pass yieldable female members 11 provided with flanges 11a located between the plates 8 and 10. Each female member has a wiring terminal 12 connected therewith, all as shown in Fig. 1. The 50 female members are arranged and adapted to make electrical contact by receiving members 7, as will be described hereafter. The male portions contact with the female portions through the apertures 12 (Fig. 4) in the plates 9 and 10 but which are properly aligned so as to permit 55 said connection.

To complete the electrical connection and facilitate and prevent disengagement of portions 2 and 3, I have provided the usual form of a separable snap fastener having a socket 13 and 60 a portion 14 adapted to rigidly secure the plates

8, 9 and 10 together, and which also holds a wiring terminal 15 to plate 8. The stud member 16 provides a similar portion to 14 and for the same purpose, and secures to the plate 5 a wiring terminal 17.

5 The wiring of the electrical contact device is as follows. A cable carrying a number of wires is inserted through the aperture 18 of the housing 1 and the wires of the cable are soldered to the wiring terminals 12 and 15. Similarly, 10 a connection is made in housing 1a by inserting a cable through aperture 19 and soldering the wires to terminal 17 and by inserting other wires of the cable through apertures 20 (Figs. 2 and 3) in plates 4 and 5 and soldering them 15 within the tubular portions of the member 7 in the usual manner.

Thus far I have broadly described a device which is well-known in the art, to which no particular claim in itself is drawn, but I shall now 20 describe improvements in construction which have been introduced to overcome certain defects only found in actual practice. Certain of these defects of a separable contact device as illustrated herein have been found when the number of male 25 and female elements were increased beyond a certain number and misalignment of the contacts occurs. It is understood by those acquainted with the art to which this device pertains that the reason for the different sized male and female 30 portions is for the purpose of making the correct electrical contact between certain portions of the socket. If this were not done, short circuits would occur. Up to a certain point, as mentioned heretofore, these different sized members 35 provided a correct method of assembly, but it was found that very often an operator would try to insert a large male element into a smaller female or socket element with the result that, using sufficient pressure, the supporting plates would 40 split or crack and henceforth the parts would be quite useless. It would be easy to see how this could happen as the contact devices were located on the circumference of a circle, especially with the apertures quite close to each other. To overcome 45 this defect, I have arranged to have the male and female contact members located on the supporting plates on the circumferences of eccentric or concentric circles so that, unless proper alignment of the elements is obtained, it is absolutely impossible to insert the larger member into a smaller one as it was when the members were all on the same circumference because they are, except in the correct position, entirely out of alignment. Figs. 2 and 3 illustrate the members 50 arranged on the circumferences of eccentric circles as described above.

55 This feature of my invention has been tried out and found to work with absolute satisfaction and it is therefore a distinct improvement in the art 60

to which it pertains. Furthermore it permits the use of a greater number of terminals without weakening the structure.

It has also been found that previous methods of holding the housing to the supporting plates were unsatisfactory and uncertain. Therefore, I have provided elements that improve the holding power and facilitate assembly. The specific improvement illustrated includes a shoulder presenting projection 21 projecting inwardly from the peripheral wall at the inner side of the housing 1 and adapted to fit between supporting plates 8 and 9. I also provide a small projection 22 extending directly from the end of the housing and adapted to fit into a notch 23 in the plate 8. The plate 8 is slightly smaller than the plate 9 and is provided with a number of cut-away straight sides 24 (Figs. 2 and 3) for the purpose of assembly.

To assemble the housing 1 to the rest of the structure, it is brought up to the supporting plates 8, 9, and 10 so that the plate 8 enters the housing and the shoulder 21 rests against the plate 8 and adjacent the straight side 24 of plate 8. At that time the projection 22 rests against the plate 9. Thereafter the housing is pressed against the plates 8 and 9. As these aforesaid plates are yieldable and resilient, the housing is permitted to rotate freely until the projection 22 snaps into the notch 23, whereupon the housing is firmly held to the supporting plates and resists any outward separating force by reason of the fact that the shoulder 21 is held between the plates 8 and 9. The notch 23 serves to limit the extent of rotation of the housing at a point where the shoulder 19 is best held by plates 8 and 9.

If it is desired to separate the housing from the supporting plates so that repairs or connections may be made, it is only necessary to pull the housing 1 away from the plate 8 and then rotate the housing from the position shown in Fig. 3 to the position shown in Fig. 2. During this operation the plate 9 yields to permit the projection 22 to ride over it while the shouldered projection 21 is being turned to a position where it is released from between the plates.

This new and improved method of assembling a cable plug to plates supporting electrical contact devices is simple, easy and positive in action and may be readily assembled or disassembled but positively resists any accidental separation.

While I have described and illustrated new and useful improvements in electrical socket devices of the class described, I do not wish to be confined thereto because the scope of my invention is best defined in the following claims.

I claim:

1. A device of the class described including a contact-carrying plate structure having two superposed plates of insulating material yieldable away from each other adjacent to their peripheries, means between said plates to maintain them in spaced relation, one plate being smaller than the other and having cut away portions at its periphery, a cup-shaped housing for assembly with said contact-carrying plate structure and a plurality of inwardly extending shoulder-presenting projections on the wall of said cup-shaped housing adapted to pass by said smaller plate at the cut away portions thereof and engage between said plates upon rotation of said housing relative to said plate structure.

2. An electrical contact device of the class de-

scribed comprising, in combination, two plates and means between them holding them in spaced relationship, a hollow cup-shaped housing having a projection integral with the peripheral wall and extending beyond the free edge thereof and having a shoulder surrounded by said wall and projecting between said plates to hold the housing in assembly with said plates, one of said plates being yieldable to pass by said projection and said plate having a notch at its periphery receiving said projection when said parts are in a predetermined relationship to prevent accidental rotation of the housing relative to the said plates.

3. An electrical contact device of the class described comprising, in combination, two parallel generally circular plates superposed in spaced relation, means operably maintaining the spaced relation of said plates, one of said plates carrying a plurality of contact devices projecting from one side thereof, said plate being yieldable and having a notch at the periphery thereof, the other of said plates being smaller in diameter than the first mentioned plate and having a portion cut away forming a straight side and a housing having a peripheral wall, a projection integral with the wall and extending beyond the end of said housing and means providing a shoulder within said housing extending inwardly adjacent the end thereof, said housing adapted to be releasably engaged with said plates by bringing said shoulder up to the straight side of said second mentioned plate and thereafter rotating said housing relative thereto whereby said shoulder is rotated between said plates to a position bearing against one of said plates and said projection rides around and flexes the notched plate until it snaps into said notch thereby holding the parts against accidental rotation.

4. An electrical contact device of the class described comprising, in combination, two plates and means between them holding them in spaced relation, a housing having a peripheral wall, a projection extending beyond said wall at its end and a projection within the housing integral with said wall and having a shoulder adapted to project between said plates to secure the housing to the plates, one of said plates having a cut-away portion to pass the shouldered projection and the other of said plates being yieldable and having a notch whereby said first mentioned projection is adapted to snap into said notch by the yielding of said plate when said housing is rotated against the plate carrying said notch.

5. A device of the class described including a contact-carrying plate structure having two superposed plates of insulating material, means between said plates to maintain them in spaced relation, one plate being smaller than the other and having a rounded periphery with cut-away portions, the larger plate being resilient and having a small notch therein, a cup-shaped housing having a small projection at its open end adapted to enter said notch, and a plurality of inwardly extending shoulder-presenting projections on the wall of said cup-shaped housing adapted to pass by said smaller plate at the cut-away portions thereof and engage between said plates upon rotation of said housing relative to said plate structure, and said small projection entering said notch to hold the parts against accidental dis- assembly after having been assembled.

CARL L. KNUTSON.
